UNITED STATES PATENT OFFICE.

JAMES C. GORMAN, OF MANSFIELD, OHIO.

POWER DIAPHRAGM PUMP.

Application filed February 8, 1926. Serial No. 86,890.

This invention relates to pumps, and more particularly to power diaphragm pumps especially designed for pumping muddy water out of trenches, foundations, 5 bridge footings and excavations and for general drainage purposes.

One object of the invention is to provide a simple, efficient and durable pump of the character referred to consisting of few parts 10 which are adapted to be easily assembled or taken apart and in which the suction and discharge valves are easily accessible for cleaning purposes or for removing and replacing the diaphragm and suction valve.

Other objects are to provide a diaphragm pump having a base portion, a spout and a jack all cast or formed in one piece, with a ledge at the base of the jack on which the periphery of the diaphragm rests, together 20 with means for clamping the diaphragm down upon the ledge, including a clamping ring which is removably secured and held in place by means of bolts inserted through radial projections on the clamping ring and 25 radial extensions of the ledge of said main casting, conforming to the shape of the projections on the clamping ring so that the diaphragm may be removed and replaced without dismantling the pump by simply 30 removing the bolts which secure said clamping ring to the main casting and the nuts on the ends of two bolts which secure the valve seat of the discharge valve to the diaphragm around a central discharge opening therein.

Another object is to provide a discharge 35 valve having a ball-and-socket-joint connection with the valve stem to insure a perfect seating of the valve when the parts are not assembled in perfect alinement as when the 40 axis of the valve stem or the socket in which it is guided in its up and down movements in the plunger connecting rod is not exactly perpendicular to the valve seat.

Another object is to provide a suction 45 valve which is yieldingly supported in operable relation to an inclined seat formed on the inlet end of the suction pipe coupling in such manner as to be easily accessible for renewal or repairs or for cleaning; the 50 valve being pressed to its seat by a stout

spring having one end seated against the back of the valve and the other end seated against a superposed abutment on the main casting.

The invention will first be hereinafter 55 more particularly described, with reference to the accompanying drawings, which are to be taken as a part of this specification, and then pointed out in the claims at the end of the description.

In said drawings, Fig. 1 is a plan view;

Fig. 2 is a vertical sectional longitudinal elevation of a power diaphragm pump embodying my invention;

Fig. 3 is a horizontal sectional view, taken 65 on the line 3—3 of Fig. 2;

Fig. 4 is a fragmentary detail view of a broken away portion of the pump, taken 70 on the line 4—4 of Fig. 3; and

Fig. 5 is a fragmentary detail view, taken 75 on the line 5—5 of Fig. 3.

Referring to said drawings, in which the same reference letters are used to denote corresponding parts in different views, the pump shown resembles in general exterior 75 appearance the pump for which I have heretofore obtained Patent No. 1,447,074, but it differs therefrom very materially in important features which will be hereinafter set forth. The letters A, J and S denote, 80 respectively, the base, the jack and the spout of my improved pump, all in one piece, preferably a single casting upon which is mounted, in suitable bearings, a crank-shaft 85 B which is geared to a counter-shaft C which carries at one end a band wheel or pulley C¹ for connection with a belt driven from a power engine or other driving means. Said pulley may of course be replaced, if desired, by a driving gear for direct connection with the engine. The crank-shaft is journaled in suitable bearings therefor supported on brackets mounted on the jack J and has secured thereto a hollow or axially 90 bored pitman or connecting rod D on the lower end of which is a cross-head or bar d having apertured ends through which are inserted stud bolts E and E¹ for securing a valve-seat to said cross-head. The bolts E and E¹ pass downwardly through upright 95

100

tubular members f of a valve-seat casting having a central opening therein around which is formed an upwardly extending annular portion f^1 , which forms a seat for a discharge valve F , when brought into valve-seating position. The lower ends of the bolts E and E^1 are passed through the inner portion of the diaphragm H surrounding a central discharge opening therein and are 10 screwed into interiorly threaded sockets in a plunger ring or casting G , while the upper ends of said bolts have nuts e and e^1 screwed thereon for holding the assembled parts together. Within the axial bore of the connecting rod D is slidably fitted a valve-stem I having a ball-shaped lower end i and a stuffing-box-like connection with the discharge valve, and a coiled or other suitable spring K is placed on the valve-stem between the stuffing-box and cross-head d so as to exert a yielding pressure on the valve tending to force it to its seat, while permitting it to yield against counter pressure tending to raise the valve. The valve F has a facing f^2 of flexible material consisting preferably of standard sheet rubber packing clamped between upper and lower members or metal parts f^2 and f^3 which are secured together by a fastening bolt f^4 screwed therein. On the free end of the bolt is screwed a lock nut f^5 for holding the several parts in assembled relation. The metal part or valve backing f^2 has a central hollow boss or hub-like projection f^6 therein which is interiorly threaded and a nut f^7 revolvably fitted on the valve-stem I overlying the ball i is screwed into said boss so as to provide a ball-and-socket-joint connection between the valve and the valve-stem and provide means for holding packing material around the ball-shaped end of the valve-stem. By these means the valve will always seat accurately, even though the axis of the bore in the connecting rod guiding the valve stem is not exactly perpendicular to the valve-seat and although the valve-seat when bolted to the connecting rods E and E^1 may not be in perfect alignment with the valve, as would otherwise be necessary to insure a perfect seating of the valve. The ball-and-socket-joint connection automatically takes care of any misalignment. The base portion of the main casting is cast or formed with a water passage connecting the suction and discharge valves which are placed therein, and the discharge valve actuating mechanism is supported on the superposed jack with the connecting rod depending through an opening in the top thereof and at the junction of the base and jack there is formed a ledge L on which is seated the outer edge or peripheral portion of the diaphragm H , which is clamped between said ledge and an overlying clamping ring M which is pref-

erably constructed in two substantially semi-circular parts m and m^1 having laterally projecting apertured lugs m^2 and m^3 , respectively, which are co-incident with outwardly extended portions or projections l of the ledge L to provide seats for the overlying clamping ring projections, the latter being suitably apertured to register with apertures in the underlying extensions of the ledge to which the clamping ring is secured by set screws or bolts N inserted from above through the registering apertures in said clamping ring and ledge; said bolts having nuts n screwed on their lower ends on the underside of said ledge for securing the parts together, as more clearly shown in Fig. 4 of the drawings. As shown, diametrically opposite apertured lugs on the two members of the clamping ring are so arranged that the lugs on one part will overlap and rest upon the corresponding lugs of the other part and the fastening bolts N at these two points pass through the overlapped portions of the lugs and through registering apertures in the underlying ledge on the main casting. The overlapping portions of the lugs m^2 and m^3 of the clamping ring, at the point where the two parts of the ring are joined together, are of wedge-shaped form, as shown in Fig. 5, so as not to weaken but give the greatest strength possible at this point. The water passage in the base portion of the main casting terminates at one end in a tubular boss or projection O to which is secured in any suitable manner a removable cap-plate or cover o , preferably by means of bifurcated lugs o^1 formed on the outside of the casting and adapted to receive fastening bolts o^2 which are screwed into nuts fitted in suitable recesses in said lugs to prevent rotation of the nut. The terminal of the water passage diametrically opposite the closure o is in the form of a tubular projection P which has an end flange p and an opening p^1 in its top, over which is fitted a cover-plate R for closing said opening. A suction pipe coupling T is bolted or otherwise secured to the flange p of the tubular projection P for the attachment thereto of a hose or suction pipe. The suction coupling T has an oblique or inwardly inclined inner end portion t against which is seated a valve U which preferably has a metal back u and a rubber sheet facing u^1 which is secured to a block V which in turn is secured on the upper side of the inner end of the suction coupling T by means of a set screw v so that by removing the cover R the valve U may be removed by simply unscrewing the set screw v . On the metal back u of the valve U is formed a boss u^2 against which is seated one end of a stout coiled or other suitable spring W , for forcing the valve to its seat; the other end of the spring being seated in a

recess *w* on the underside of the main casting.

I thus provide a very simple and inexpensive suction valve construction in which the valve is yieldingly pressed toward its seat by means of a spring which is supported between a boss on the back of the valve and a superposed abutment on the main casting without other fastening means.

10 Some of the advantages of a pump of the described construction over diaphragm pumps as heretofore ordinarily constructed may be enumerated as follows. It consists of comparatively few parts of simple design 15 adapted to be easily assembled or taken apart, thus reducing the cost of manufacture and the time required in assembling and securing the several parts together. Easy access to the interior of the pump is 20 afforded by simply removing the cover of the cleanout opening, and the diaphragm may be removed and replaced without dismantling the pump or removing the jack or spout. Easy access is afforded to the suction valve for cleaning or removing it to 25 replace a worn or broken part. Increased strength and reduced cost of manufacture are attained by constructing the base, jack and spout in a single piece, and simplicity 30 and strength are combined in the general arrangement of parts.

The discharge valve, which is guided entirely by its upward projecting stem, gives a full, free, non-clogging discharge opening 35 so essential to continuous uninterrupted operation of the pump, and this valve is spring loaded to insure quick action. The raised, rounded seat of this valve will not permit particles to lodge on it and thereby prevent the valve from closing so as to destroy the suction. The suction valve is also spring loaded for quick action and its seat is in such oblique position that solids will not remain on it.

40 Having thus described my invention, what I claim as new and desire to secure by Letters Patent of the United States is:

1. In a diaphragm pump, a combined base, jack and spout formed in one piece with a ledge uniting the base and jack; said base being hollow and of approximately square form and having a water passage therethrough, and said jack being bulged at the corners of the base so as to form recesses therein coincident with apertures in said ledge, a clamping ring arranged to rest upon the periphery of a diaphragm resting on said ledge and having radially extending apertured projections coincident with said recesses, and fastening bolts inserted through the apertures in said projections and ledge for clamping the periphery of the diaphragm between said ring and ledge.

65 2. The combination, in a diaphragm

pump, of a combined base, jack and spout formed integrally with a ledge uniting the base and jack; said base being hollow and of approximately square form and having a water passage therethrough and the vertical wall of the jack adjacent said ledge being bulged outwardly so as to provide recesses on the inner side thereof at the corners of the base, a diaphragm fitted within an opening through the top of said base 70 with its peripheral portion resting on said ledge and carrying a discharge valve controlling the outlet from said passage, a clamping ring resting on said peripheral portion of said diaphragm and having radial projections coincident with and protruding into said recesses, and fastening bolts inserted through registering apertures in said projections and ledge for clamping 80 said diaphragm between said ring and ledge.

3. In a diaphragm pump, a combined base, jack and spout formed integrally with a ledge uniting the base and jack; said base being hollow and having a water passage 90 therethrough and provided at one side thereof with an integral tubular projection having an inlet valve seated therein, a clamping ring resting on the periphery of a diaphragm resting on said ledge, bolts 95 passing through registering apertures in said ring and ledge for clamping said diaphragm therebetween, and a discharge valve controlling the outlet from said passage through said diaphragm.

4. In a diaphragm pump, a combined base, jack and spout formed in a single piece with a ledge uniting the base and jack; said base portion being hollow and having a water passage therethrough and an integral 105 tubular projection at one side thereof having an inwardly-opening suction-valve seated therein and also having on its underside adjacent said valve an integral inwardly inclined abutment, a coiled spring having one 110 end seated against said abutment and its other end seated against the back of said valve, a clamping ring resting on the periphery of a diaphragm resting on said ledge, bolts passing through registering 115 apertures in said ring and ledge for clamping said diaphragm therebetween, and a discharge valve controlling the outlet from said passage through said diaphragm.

5. The combination, in a diaphragm pump, of a combined base, jack and spout formed integrally with a ledge at the junction of the base and jack; said base being hollow and of approximately square form, and said ledge having outwardly extended 125 projections at the four corners thereof while the vertical wall of the jack at the base thereof is bulged outwardly coincident with said projections, and a clamping ring composed of substantially semi-circular 130

separable parts each having diametrically opposed outwardly extending projections coincident with the projections on said ledge and seated thereon within the recess formed by the bulges; the projections on said clamping ring having inclined surfaces fitting one upon the other and secured to-

gether by fastening bolts inserted through registering openings therein and in said ledge.

In testimony whereof I affix my signature.

JAMES C. GORMAN.
